UNITED STATES PATENT OFFICE

EMIL KÖRTING, OF SAN FRANCISCO, CALIFORNIA

LOG-HOLDING DEVICE FOR FLAT CARS

Application filed August 10, 1929. Serial No. 385,038.

My invention relates to improvements in a log holding device for flat cars, and it consists in the combinations, constructions and arrangements hereinafter described and 5 claimed.

An object of my invention is to provide a log holding device for flat cars which can be moved into an out of the way position for permitting the logs to be rolled off from the 10 flat car rather than be lifted.

A further object of my invention is to provide a device of the type described in which the log-holding mechanism may be released from either side of the car or from either end.

15 A further object of my invention is to provide a device of the type described which is extremely simple in construction and which makes use of a positive locking mechanism.

Other objects and advantages will appear 20 as the specification proceeds, and the novel features of the device will be particularly pointed out in the claims hereto attached.

My invention is illustrated in the accompanying drawing, in which:

25 Figure 1 is a top plan view of the device, Figure 2 is a side elevation,

Figure 3 is a section along the line 3—3 of Figure 1,

Figure 4 is a section along the line 4—4 of 30 Figure 2, and

Figure 5 is a perspective view of one of the log-holding members.

In carrying out my invention I make use 35 of a flat car indicated generally at 1. The flat car has a floor 2 and carries angle irons 3 that have one of their legs secured to the car body and their other legs projecting above the top of the floor. The upper edges of the angle irons 3 are serrated as at 4.

40 As many angle irons as desired may be used. The angle irons are disposed in pairs as shown in Figure 1, and members 5 are disposed between them. The members and the angle irons form openings 6 in which log-retaining members 7 are slidably disposed. There are two members 7 associated with each pair of angle irons.

45 The particular shape of the member 7 is shown in Figure 5. The member has a rack portion 8, guide flanges 9, and an inclined

upper surface 10. Figure 4 shows how the flanges 9 slide in guide members 11, the latter being secured to the car frame 1 by bolts 12 or other suitable fastening means.

The members 7 are moved vertically by 55 pinions 13, these being mounted upon shafts 14, the latter in turn being actuated by hand wheels 15 or other suitable mechanism.

In Figure 1 I have shown a flat car provided with four hand wheels 15, and each of these hand wheels actuates two members 7. 60 Figure 3 shows how the members 7 ride between rollers 16, and further shows how the member is held against the pinion 13 by a part of the flat car frame.

65 From the foregoing description of the various parts of the device, the operation thereof may be readily understood.

If desired, all of the members 7 may be moved below the top of the car during the 70 loading of the logs thereon. The usual practice, however, is to leave the members 7 projecting above the top as shown to the left in Figures 2 and 3. The logs are lowered upon the flat car and are held against rolling laterally by the members.

75 When removing the logs from the car, the members 7 on the removal side of the car are lowered. If the logs are small, only two members on the side need to be lowered, while if the logs extend the entire length of the car, all four members are lowered. Any means for moving the logs laterally after the members have been lowered may be resorted to for rolling the logs off from the flat car.

80 It should be noted that the logs are really supported by the vertical edges of the angle irons 3. The teeth 4 on the channel irons prevent sliding of the logs. In Figure 3 I show a locking device used in connection with each of the hand wheels 15. A ratchet 17 is keyed to the shaft 14 and is held against a clockwise rotation by a pawl 18. The pawl in turn is locked against accidental dislodgement by a keeper 19. Before the pawl 18 can be removed from the ratchet 17, the keeper 19 must be swung into inoperative position. If the keeper is in operative position, it holds the pawl against the ratchet and prevents the shaft from being rotated in either 85 90 95 100

direction. The end of the shaft 14 is made square for permitting a crank (not shown) to be applied for giving the shaft an initial turn, after which the hand wheel may be turned.

Although I have shown and described one embodiment of my invention, it is to be understood that the same is susceptible of various changes, and I reserve the right to employ such changes as may come within the scope of the invention as claimed.

I claim:

1. In combination, a supporting surface, pairs of angle irons having their vertical sides projecting above the surface, the upper edges of the sides being serrated, log-holding members disposed between said pairs of angle irons and being movable vertically, guides for said members including rollers, each member having a rack, a pinion meshing with the rack, shafts connecting the pinions together in pairs, hand wheels for rotating the shafts, a pawl and a ratchet for securing the shaft against movement in one direction, and a keeper for locking the pawl in place for preventing movement of the shaft in either direction.

2. In combination, a supporting surface, pairs of angle irons having their vertical sides projecting above the surface, the upper edges of the sides being serrated, log-holding members disposed between said pairs of angle irons and being movable vertically, guides for said members including rollers, each member having a rack, a pinion meshing with the rack, shafts connecting the pinions together in pairs, and hand wheels for rotating the shafts.

3. In combination, a supporting surface, pairs of angle irons having their vertical sides projecting above the surface, the upper edges of the sides being serrated, log-holding members disposed between said pairs of angle irons and being movable vertically, guides for said members, each member having a rack, a pinion meshing with the rack, shafts connecting the pinions together in pairs, hand wheels for rotating the shafts, a pawl and a ratchet for securing the shaft against movement in one direction, and a keeper for locking the pawl in place for preventing movement of the shaft in either direction.

4. In combination, a supporting surface, pairs of angle irons having their vertical sides projecting above the surface, log-holding members disposed between said pairs of angle irons and being movable vertically, guides for said members, each member having a rack, a pinion meshing with the rack, shafts connecting the pinions together, hand wheels for rotating the shafts, a pawl and a ratchet for securing the shaft against movement in one direction, and a keeper for lock-

ing the pawl in place for preventing movement of the shaft in either direction.

5. In combination, a supporting surface, pairs of angle irons having their vertical sides projecting above the surface, log-holding members disposed between said pairs of angle irons and being movable vertically, guides for said members, each member having a rack, a pinion meshing with the rack, shafts connecting the pinions together, and hand wheels for rotating the shafts.

6. In combination, a supporting surface, log-holding members movable from a position beneath the surface to one extending above the surface, each member having a rack, a pinion meshing with the rack, a shaft for rotating the pinion, a pawl and ratchet for securing the shaft against movement in one direction, and a keeper for locking the pawl in place for preventing movement of the shaft in either direction.

7. In a log-holding device for flat cars, a supporting surface, a guideway depending from said surface, a log holding member slideable in the guideway, rollers contacting with the member, means for raising and lowering the member, the top of said member being inclined for aiding in the engagement with and the disengagement from the logs.

8. In a log holding device for flat cars, a pair of members, means for spacing said members apart, log-engaging members movable vertically between the first members, means for moving said log-engaging members, and means for locking said moving means, said log-engaging members having inclined tops.
